R. DAVIS

SHANK IRON

Filed Oct. 5. 1923

ROBERT DAVIS,
INVENTOR

BY *O. W. Smith*
his ATTORNEY.

UNITED STATES PATENT OFFICE.

ROBERT DAVIS, OF BROOKLYN, NEW YORK.

SHANK IRON.

Application filed October 5, 1923. Serial No. 666,668.

My invention relates generally to the manufacture of footwear and refers more especially to the step-in shoe production which involves the use of fastening means 5 to attach a shoe-shank to the sole of a partially completed shoe.

According to the present invention, a shoe-shank of the general type, comprising a reenforced leather member, is superposed 10 on the arch in a shoe after the upper has been sewn to the sole. The position assumed by the shank brings the forward end well up towards the toe and under the overhanging vamp of the upper, and as a consequence it is very difficult to insert a fastening means in the forepart of the shank and still more difficult to drive the fastening means through the shank and into the sole. The application of an adhesive 15 between the adjacent faces of the shank and sole assists in holding the former in position while the operator inserts and secures the fastening means, usually a flat headed tack, into the sole, but nevertheless the operation is still difficult and uncertain and results in many shoes being turned out having the toe of the shank loosely resting on the sole beneath the insole.

With the foregoing in mind it is the purpose of the present invention to overcome the difficult operation of using tacks as fastening means for the shank and insole; and I accomplish this purpose by providing the reenforcing member of the shank with integral engaging teeth which are driven directly into the insole when the shank is adjusted to its correct position upon the arch of the shoe.

The invention therefore, briefly stated, 40 refers to a shank-iron of the types which are disclosed in my co-pending applications, Serial Numbers 655,194 and 666,667 (which latter application has matured into Patent Number 1,545,087, dated July 7, 1925), 45 which comprise forked ends providing tapered prongs adapted to be clenched over the shank material and engaging teeth projecting in the opposite direction from the forked ends to engage the shoe insole.

My invention is illustrated in the accom-

panying drawing in which Figure 1 is a longitudinal sectional view of a shoe embodying my improved means for attaching the shoe-shank to the sole; Figure 2 is a perspective view of a shank-iron showing 55 the engaging teeth disposed at opposite ends thereof; Figure 3 is an end view of a shank-iron; Figures 4 and 5 are side elevational views of a shank showing the depending integral attaching means applied to different 60 forms of shank-irons.

Referring to the drawings, and particularly to Figure 1, 10 designates the sole of a shoe and 11 the upper. The sole is curved upwardly at its mid portion to form the 65 arch 12, and superposed over the arch is a shoe shank 13, which comprises a leather piece having a rear portion 14 cut to fit the heel of the shoe and a downwardly curved forward portion 15 adapted to rest upon the arch and extend to a point slightly in advance thereof.

The shoe shank 13 is further provided with a reenforcing shank iron 16 comprising a narrow bowed strip of metal having a longitudinal rib separated into sections 17 by means of transverse ribs 18 which give the necessary resiliency to the iron. In the form of iron shown in Figure 5 there is only one resilient rib disposed in the mid portion thereof. In both modifications the ends of the iron are split to provide two outside prongs 19 and an inside prong or engaging means 20. The outside prongs are bent upwardly at an angle to the plane of the iron and the inside prong is bent downwardly in a direction opposite to that of the prongs 19. To enable the inside prong 20 to firmly engage in the sole of the shoe the shoe iron is provided with barbs 21, as shown clearly 70 in Figure 3.

In operation, the shank constructed in accordance with my invention is merely placed in position within the shoe and the shoe-last inserted, whereupon the depending engaging members or prongs 20 are forced into the adjacent material of the sole 10 and the barbs prevent them from being drawn outwardly again. It is to be particularly noted that shanks attached in this 80 85 90 95 100

manner retain the same degree of freedom to adjust themselves to the arch beneath the instep of the wearer as shanks attached by tacks or other separate fastening means.

5 What I claim is:—

A shank-iron comprising a plate provided at each end with outside prongs adapted to

clench over a shoe shank and an intermediate prong adapted to be driven into a shoe sole.

In testimony whereof I have affixed my signature.

ROBERT DAVIS.
